UNITED STATES PATENT OFFICE.

THOMAS WEBSTER CAMPBELL, OF ENERGY, SOUTH CAROLINA, ASSIGNOR
OF TWO-THIRDS TO QUINTON J. HOKE AND WILLIAM M. BIGGER, OF
SAME PLACE.

SUBSOIL-PLOW.

SPECIFICATION forming part of Letters Patent No. 639,356, dated December 19, 1899.

Application filed April 28, 1899. Serial No. 714,779. (No model.)

To all whom it may concern:

Be it known that I, THOMAS WEBSTER CAMPBELL, a citizen of the United States, residing at Energy, in the county of York and State 5 of South Carolina, have invented a new and useful Subsoil-Plow, of which the following is a specification.

My invention relates to improvements in plows in which I employ a subsoiling landside and share in connection with a revoluble furrow-turning moldboard adapted to be drawn through the ground without material increase in the draft on the team, because the subsoiler thoroughly breaks the ground 15 in advance of the moldboard, and thereby reduces friction to a minimum.

A further object of the invention is to provide a moldboard which may easily be reversed at the end of the furrow without taking off said moldboard, thereby adapting the implement to service as a hillside-plow, because the moldboard may occupy a position on either side of the beam, and with said reversible moldboard is combined means by 25 which it may be held at different angles to the line of draft.

A further object is to provide means by which the revoluble moldboard may be adjusted vertically to suit the depth of the plow, 30 said means serving to hold the moldboard in either of its several adjustments.

With these ends in view the invention consists in the novel combination of elements and in the construction and arrangement of 35 parts, which will be hereinafter fully described and claimed.

In the drawings, Figure 1 is a perspective view of a subsoiling moldboard-plow constructed in accordance with my invention. 40 Fig. 2 is a side elevation thereof. Fig. 3 is a rear elevation of the same. Fig. 4 is a vertical section through the means for reversely supporting the moldboard, the plane of the section being taken transversely through the 45 hollow standard and the moldboard and showing the spindle and locking device in elevation. Fig. 5 is a plan view of the parts shown by Fig. 4. Fig. 6 is a detail perspective view of the tubular standard which carries the 50 revoluble moldboard. Fig. 7 is an enlarged detail section through the bearing for the

revoluble moldboard. Fig. 8 is a detail cross-section of the scraper-shovel. Fig. 9 is a detail cross-section through the beam to show the brace therefor.

55

The same numerals of reference denote like parts in each of the several figures of the drawings.

The beam 10 of my improved plow is constructed of a single flat piece of metal, preferably of steel, to secure maximum strength without increase in the weight of the implement. To this beam is firmly secured the upright stock or foot 11, and through the upper end of said stock and the beam are passed 60 the fastening-bolts 12. The stock or foot is also constructed of metal and its front edge is beveled or inclined at 13 to produce a cutting edge on the front side of the stock.

The landside 14 is cast in a single piece of 65 metal, with a lateral foot-flange 15, and the upright part of the landside is inclined in a direction from the front end to the beveled edge 13 of the stock, said inclined edge of the landside being beveled transversely to produce 70 the cutting edge 16, which practically joins with the cutting edge 13 of the stock, whereby the landside is made to serve the purpose of a colter in cutting through the soil, and the edges 13 16 of the stock and landside coact to 75 sever the soil when the implement is drawn through hard ground. The sole-flange of the landside is extended beyond the colter edge 16, and in said landside is produced a notch 17, which is adapted to receive a part of the 80 point or share 18. The point is arranged to overlap the sole-flange at the front end of the share or landside, and it is fastened firmly in place by a vertical bolt 19.

To cut roots and obstructions in the path of 85 the subsoiling-plow I employ a rotary colter 20, which is suspended in a position over the colter of the landside by means of a hanger 21. The hanger is fastened to the beam in advance of the attachment of the foot or stock 90 thereto, and said hanger has a journal on which the rotary cutter 20 is mounted to rotate freely.

The handles 22 of the plow are fastened securely to the beam by a suitable bolt, and these handles are united together by a transverse tie-bar 23. The handles are stayed in 95

proper position with relation to the beam by the braces 24. These braces are fashioned peculiarly to stay the handle-bars and to serve as a guide for the carrying-bar of the revoluble moldboard. As shown more clearly by Fig. 3 of the drawings, the lower part of the braces 24 have straight parallel lengths 25, arranged to loosely embrace the rear end of the flat beam and united firmly thereto by one or more transverse bolts 26. The straight lengths 25 of the braces are attached together by a transverse bolt or pin 27, located at a suitable height above the beam, and above said bolt or pin 27 the braces diverge laterally, as at 28, in a manner to have the ends thereof bear against the inner faces of the handle-bars, said diverging ends of the braces being fastened to the handle-bars by the bolts 29.

30 designates the carrying-bar for the revoluble moldboard. This carrying-bar is made curved or angular, as at 31, and its vertical member is prolonged or extended in a downward direction and is fashioned to produce an elongated spindle 32, which is of circular cross-section. At a point between the flat carrying-bar and the cylindrical spindle a locking-disk 33 is fastened firmly to the carrying-bar or made integral therewith for a purpose which will presently appear. A pair of bars 34 are made fast to the carrying-bars 30 by welding said bars 34 to the front end of the carrying-bar, and said bars 34 are extended forwardly above the plow-beam and the front ends thereof are bent or curved in a downward direction. The curved front ends of said bars 34 lap the plow-beam 10, and a horizontal bolt 35 passes through the front ends of the bars and the beam in order to pivotally attach the carrying-bar to said beam. This carrying-bar is fitted slidably in the slot or space which is formed by and between the parallel lengths 25 of the braces which afford lateral supports for the carrying-bar, and as said bar 30 is connected by a horizontal pivot-bolt to the beam it may be raised or lowered in a vertical direction to regulate the position of the revoluble moldboard relatively to the subsoiling-plowshare. As one means for supporting the carrying-bar in either of its several positions I employ an adjusting-bar 36, which is pivotally attached by a bolt 37 to the carrying-bar, and this adjusting-bar is provided at its upper end with an offset-handle 38 and with a series of notches 39. It is evident that the handle may be manipulated to raise or lower the bar 30, and the handle may then be moved on its pivot 37 to make the pin or bolt 28 enter either of the notches 39 in said adjusting-bar, whereby the bar 30 may be suspended or supported in its adjusted position.

To provide for the reversal of the revoluble moldboard and to furnish a secure and substantial support therefor, I employ a tubular standard 40, which is fitted snugly to the vertical spindle 32 of the carrying-bar 30. This tubular standard is preferably cast in a single

piece of metal, with an integral disk-shaped head 41 at its upper end, and this head is adapted to abut or bear against the locking-disk 33 on the carrying-bar. The head of the tubular standard is provided on one side thereof with vertical apertures 42 43, and on the other side of the vertical axis of said standard the head is, furthermore, provided with other apertures 44 45, the apertures 44 and 45 being located at diametrically opposite points for a purpose which will presently appear. The standard is, furthermore, provided with a radial pin or stud 46, which enters an annular groove 47, provided in the spindle 32 of the carrying-bar, and this construction permits the standard 40 to turn freely on the spindle without moving endwise on said spindle, thus connecting the standard and spindle together in a manner to prevent vertical displacement of the standard.

The tubular standard has its lower end enlarged to form a foot 48, and in one side of this foot is produced a cylindrical cavity 49, 90 which constitutes a bearing for the rotary disk, and arranged centrally in this cylindrical cavity or bearing 49 is a journal-pin 50, which is made fast with the closed side or end of the foot 48. The rotary disk 51, which 95 constitutes the moldboard, is a single piece of metal of concave or dished contour, and on the convex face of this disk is provided a cylindrical hollow journal or stud 52. (See Figs. 4 and 7.) This stud constitutes the hub 100 of the revoluble disk, and the stud is fitted in the cavity or bearing 49, while the journal-pin 50 enters the opening of the hollow stud 52, whereby the rotary disk is connected to the tubular standard by a joint which permits the disk to rotate freely on the standard, 105 which excludes dirt from the bearing, and which minimizes the friction between the co-acting elements of the disk and the standard.

The disk 33 of the carrying-bar is provided with a horizontal plate 53, which extends rearwardly from the disk 33 and is provided with lugs 54. (See Figs. 2, 4, and 5.) One end of a lever 55 is fitted between said lugs and is connected thereto by a pivot-bolt 56. To this lever is connected a locking-pin 57, the upper end of which is forked at 58 to embrace said lever, and the forked end of the pin is pivoted by a pin or bolt 59 to the lever 55. This lever may be raised to withdraw the locking-pin from engagement with the perforated head of the tubular standard, thus permitting the standard to be turned on the spindle in order to change the position of the rotary disk from one side to the other of the spindle. The locking-pin 57 is adapted to pass through an aperture 57^a in the disk 33 of the carrying-bar, and this pin may be fitted in either of the openings 42 to 45, inclusive, in the head 41 of the tubular standard. It will be observed that the tubular standard is adapted on withdrawal of the locking-pin to turn on the spindle of the carrying-bar, and thus the standard may be adjusted to change

the position of the rotary disk with relation to the plow-beam and the subsoiling-share thereof. The rotary disk may be adjusted to the right or left hand side of the share in order to make its concaved side face in either direction, and the tubular standard, which carries said disk, may be fastened in place by the locking-pin for the rotary disk to occupy different angles to the line of draft. When the disk occupies a position on the right-hand side of the plow, the lever may be adjusted to move the locking-pin into the aperture 42 of the standard-head 41, thus giving a certain angular position of the rotary disk to the line of draft; but if it is desired to increase this angle of the disk on the right-hand side of the plow the standard may be adjusted to bring the aperture 43 into a position to receive the locking-pin. By withdrawing the locking-pin from the head of the standard the rotary disk may be shifted by turning the standard on the spindle to the left-hand side of the plow, and the angle of the rotary disk to the line of draft may be changed by making the locking-pin fit in either of the apertures 44 or 45 on the head of the tubular standard.

From the foregoing description it will be observed that the standard and the rotary disk which is mounted thereon may be raised or lowered by adjusting the notched bar 36 into engagement with the pin or bolt 27 by the braces 24. This provides for the vertical adjustment of the rotary disk with relation to the share; but such vertical adjustment does not interfere with the rotary adjustment of the tubular standard on the spindle in order to shift the rotary disk with relation to the share; nor does either of the adjustments heretofore described interfere with the revoluble motion of the disk on the tubular standard.

To provide for proper cleaning of the rotary disk, I employ a cleaner-shovel 60, which is provided with a shank 61, having an eye 62. An arm 63 is made fast to or integral with the head 41 of the tubular standard, and this arm is adapted to fit in the eye of the shovel-shank, whereby a binding-screw 64, which is mounted in the shank, may engage with the arm to hold the shovel in proper relation to the face of the rotary concave disk 51.

When the subsoiling-plow is used in wet land, I prefer to employ a conical drag 65, which is provided with a chain or other flexible connection 66, that is attached to the heel 55 of the share. This conical drag is adapted to trail in rear of the subsoiling-share, and it serves the purpose of opening a drain in the wet ground. A clevis 68 is connected adjustably to the front end of the plow-beam. Said beam has an inclined series of transverse apertures 69, and in its end edge is a series of notches 70. The clevis 68 is provided with two bolts 71 72, the bolt 71 fitting in either of the apertures 69, while the bolt 72 fits in either of the notches 70 in the beam, whereby the clevis may be adjusted to in-

clined or horizontal positions on the front end of the plow-beam to change the line of draft thereon.

The subsoiling-plow of my invention may be used for various purposes, and it is especially adapted for gardening purposes by truck-farmers for the cultivation of beets and cotton and for preparing the ground for planting crops. The revoluble disk or moldboard 75 is adapted to be reversed at the end of a furrow without detaching said disk from the plow, and thereby adapt the implement to hillside-work. The employment of the revoluble disk at an angle to the line of draft does 80 not materially increase the draft of the plow, because the colter and subsoiler breaks the land thoroughly and minimizes the friction, and the implement is thus adapted to perform a maximum amount of service with little attention and without material increase in the draft. The several parts of the structure are simple and durable in construction, and they are arranged for easy access to permit of the adjustment of the parts by the operator 85 stationed at the rear end of the plow.

Changes in the form, proportion, size, and the minor details of construction within the scope of the appended claims may be resorted to without departing from the spirit or sacrificing any of the advantages of this invention. I also find it desirable to provide a stay to hold the stock or foot and the beam in firm relation one to the other, and thereby brace the beam. This brace is indicated at 73 on 90 the side of the plow-beam opposite to that side to which the stock 11 is fastened, and said brace has an angular arm 74, (see Fig. 2,) arranged to have its lower end bear against and be secured to the foot or stock, as at 74^a. 105 The horizontal part of the brace is offset near the ends, as at 75, and the rear offset part of this brace is fastened to the beam by the bolts 12, which unite the stock and beam, while the front offset end of the brace is united 110 at 76 to said beam. By offsetting the brace it is spaced laterally with respect to the major length of the beam to enable the arms 34, the clamp 21, and the handles to be fitted or attached to the beam without hindrance from 115 said brace.

Having thus described the invention, what I claim is—

1. In a subsoil-plow, a combined share and landside having the inclined cutting edge 120 adapted to serve as a colter, substantially as described.

2. In a subsoil-plow, a combined share and landside having the inclined cutting edge, 16, formed with a notch, and a point secured removably to the share and fitting in the notch of the landside thereof, substantially as described. 125

3. In a subsoil-plow, the combination of a beam, a foot or stock having the cutting edge, 130 a combined share and landside having the inclined cutting edge, 16, joined to the stock to

- lie practically continuous with the cutting edge thereof, and a point secured to the share, substantially as described.
4. In a plow, the combination of a carrying-bar provided with a spindle, a standard on said spindle, a bearing fast with said standard and provided with an axial journal-pin arranged to form an annular opening within the box of said bearing, a rotary disk, and a hollow journal-stud fast with said disk, said stud receiving within itself the journal-pin and filling the space between the said pin and the box of the bearing, substantially as described.
- 15 5. In a plow, the combination with a beam, of a vertically-adjustable carrying-bar, a standard connected to said bar for adjustment in a horizontal plane thereon, and a moldboard-disk mounted revolubly on said standard, whereby the disk may rotate freely and be adjusted vertically with the bar and horizontally with the standard, substantially as described.
- 25 6. In a plow, the combination with a beam, of a subsoil-share, a rotary moldboard-disk, and means for supporting said moldboard-disk in rear of the share and for adjusting said disk in horizontal and vertical planes, substantially as described.
- 30 7. In a plow, the combination with a beam and a subsoiling-share, of a carrying-bar connected to said beam for adjustment vertically to the share, a standard mounted on said carrying-bar for adjustment in a horizontal plane thereon, a rotary disk mounted on said standard, and means for locking the standard and disk to permit the disk to assume angular positions with relation to the line of draft on either side of the beam, substantially as described.
- 35 8. In a plow, the combination with a beam, of a vertical standard connected operatively with said beam for axial adjustment in a horizontal plane, a moldboard-disk journaled on said standard to be shiftable therewith on opposite sides of the beam, and means for locking the standard and disk in different angular positions with relation to the plane of the beam, substantially as described.
- 45 9. In a plow, the combination with a beam, of a vertically-adjustable carrying-bar pivoted to said beam, a standard carried by said bar for revoluble adjustment in a horizontal plane thereon, a moldboard-disk mounted on said standard and adapted to partake of the horizontal adjustment thereof and also of the vertical adjustment of said standard with the carrying-bar, and independent locking devices for holding the carrying-bar at the desired elevation and also for holding the standard and moldboard in their adjusted positions relatively to said carrying-bar, substantially as described.
- 50 10. In a plow, the combination with a beam and handle-bars fastened thereto, of braces 65 connected to the beam and handle-bars and arranged to form a guideway, a carrying-bar pivoted to the beam and fitted slidably in the guideway of the braces, a moldboard mounted on the carrying-bar, and an adjusting-bar 70 pivoted to the carrying-bar and arranged to engage with suitable confining means supported by the braces, substantially as described.
11. In a plow, the combination with a beam, 75 of a carrying-bar provided with a spindle, a standard fitted to said spindle for rotary adjustment thereon, a moldboard connected to said standard and adapted to be shifted thereby to opposite sides of the beam, and locking 80 devices between the carrying-bar and the standard for determining the relation of the moldboard to the line of draft, substantially as described.
12. In a plow, the combination with a beam, 85 of a carrying-bar connected thereto for vertical adjustment and provided with a spindle and with a disk, a tubular standard revolubly fitted to said spindle and having a perforated head adapted to bear against the disk 90 of the carrying-bar, a moldboard mounted on said standard, a lever fulcrumed on the carrying-bar, and a locking-pin connected to said lever and adapted to engage with the head of the tubular standard, for the purpose 95 described, substantially as set forth.
13. In a plow, the combination with a beam, of a vertically-adjustable carrying-bar, a standard supported by said bar for revoluble adjustment in a horizontal plane thereon, a 100 rotary disk journaled on said standard, and a cleaning-shovel attached to the standard and arranged contiguous to one face of said disk, said shovel and disk being mounted on the standard for adjustment therewith in the 105 shiftable movement of the standard with the carrying-bar and of the adjustment of said standard on the carrying-bar independently of the movement of the latter, substantially as described.
14. In a plow, the combination with a beam, and a carrying-bar, of a standard mounted on said carrying-bar for adjustment on its axis and provided with the laterally-extended arm, a rotary disk mounted on said standard at a 115 point below the arm and shiftable with the standard relative to the line of draft, and a cleaner-shovel clamped adjustably to the arm of the standard and supported thereby contiguous to one face of the disk, substantially 120 as described.

In testimony that I claim the foregoing as my own I have hereto affixed my signature in the presence of two witnesses.

THOS. WEBSTER CAMPBELL.

Witnesses:
